LIQUID SPRAYER

Robert M. Bagley, Haddonfield, N. J., assignor to
 R. M. Hollingshead Corporation, Camden, N. J.,
 a corporation of New Jersey

Application January 4, 1934, Serial No. 705,271

8 Claims. (Cl. 299—89)

My invention relates to certain novel improvements in liquid sprayers, and it relates more particularly to manually operated liquid sprayers adapted to be attached to and to be used in conjunction with original containers of liquids to be sprayed.

One of the objects of my invention is to provide a liquid sprayer which will produce a generally continuous spray notwithstanding the intermittent operation of the air pump. A further object of my present invention is to provide a spray which will function efficiently, which will be inexpensive to produce, and which will be dependable in all positions and under all conditions of operation.

With the above and other objects in view, my invention consists of certain novel features of construction, which will appear more fully from the following detailed description and the accompanying drawing.

For the purpose of illustrating my invention, I have shown in the accompanying drawing one form thereof which is at present preferred by me, since the same has been found in practice to give satisfactory and reliable results, although it is to be understood that the various instrumentalities of which my invention consists can be variously arranged and organized and that the invention is not limited to the precise arrangement and organization of the instrumentalities as herein shown and described.

Referring to the drawing in which like reference characters indicate like parts:

Figure 1 represents a generally longitudinal sectional view of the sprayer embodying my invention.

Figure 2 represents a modified form of construction embodying my invention.

Figure 3 shows a modified form of construction in the orifice.

Figure 4 shows a further modified form of construction in the orifice.

The liquid sprayer of my present invention includes a generally cylindrical member 5 which serves as a pump cylinder. Into the front end of the cylinder member 5, a generally cylindrical air chamber 6 is telescoped;—the outer diameter of the chamber 6 being approximately the same as the inner diameter of the cylinder 5. The chamber 6 may be formed of a single sheet of metal by drawing in a dye, thereby giving it an end wall 7, and also forming a suitable flange 8 around its open end, which then forms part of an interlocking seam with the end of the cylinder 5.

cylindrical seal 5, and with a flange of a cap member or nozzle member 9.

The cap member or nozzle member 9 is preferably provided with an outwardly converging more or less conical wall 10, terminating in a slight tip 11, having a suitable aperture 12 therethrough.

A retainer plate 13 extends across the cap member 9 and is held in place by the seam 14. The seam 14 is formed in the conventional manner, by any suitable capping machine, as for instance, those used in can-making. The liquid-conducting tube 15 is extended through a suitable opening 16 in the retainer plate 13, with the end of the tube projecting into the recessed tip 11 of the cap 9. The tube 15 is soldered in place to the plate 13, by solder 17 and 18.

A screw-cap 19 is fastened to one side of the cylinder 5, near the front end thereof, as for instance, by soldering at 20, and an aperture 21 is provided through the wall of the chamber 6, through the wall of the cylinder 5, and through the top 22 of the screw-cap 19, so that free communication is established between the interior of the chamber 6 and the interior of the liquid container 23.

The opening 21 is preferably soldered around its inner wall, so as to form a seal between the interior of the chamber 6 and the interior of the cylinder 5, behind the wall 7.

The tube 15 extends through the opening 21 down into the liquid container 23, and may be bent slightly so as to extend towards the side wall of the can near the bottom thereof.

The can 23 may be any standard or conventional screw-top can serving as an original container for the liquid to be sprayed.

A check valve housing 24 is provided in the terminal wall 7 of the air chamber 6, as indicated particularly in Figures 1 and 2; this check valve housing including an annular valve seat 25, and a valve cage 26 within which a ball check valve 27 is loosely mounted. The inner end of the cage 26 is provided with perforations 28, through which air may enter into the chamber 6.

The piston 29, carried on the inner end of the piston rod 30 may be any suitable piston, as for instance, composed of the metallic follower plate 31 of a cup-shaped leather or similar washer 32, and the resilient sheet metal (phosphor-bronze or brass) retainer and expander member 33, having the serrated flange 34 adapted to bear outwardly against the flange of the cup-shaped washer 32, thereby to press it into contact with the inner surface of the cylinder 5. The piston rod 35

39 extends through an opening 35 of any suitable cylinder head 36, which may be formed of wood or similar material, and held in place by one or more set screws 37. The piston rod 30 is provided with a handle 38, and a stop washer 39, held in place by the wedged projections 40 formed of the rod 30. A helical compression spring 41 may also be provided on the rod 30 to take up the shock of any sudden withdrawal of the piston rod;— that is, to prevent the piston 29 abutting against the cylinder head 36. The opening 35 in the cylinder head may be sufficiently larger than the piston rod 30, to permit the intake of air, although if desired, an opening 42 may be provided 15 in the cylinder wall, ahead of the piston in its retracted position through which the air may also be taken in.

In the embodiment of the invention shown in Figures 1, 3 and 4, an opening 43 is also provided 20 in the plate 13, for maintaining permanent air communication between the interior of the conical portion 10 of the cap member 9 and the interior of the chamber 6.

The discharge end of the tube 15 is provided 25 with an opening (in addition to its end opening) which is in communication with the interior of the air chamber 6. In the embodiment of the invention shown in Figure 1 and Figure 2, this opening is in the form of a slot 44 cut into the tube from its end, and of a length greater than the depth of the recess of the tip 11. In the embodiment of the invention shown in Figure 3, this opening is in the form of a small round side opening 45, which may be drilled into the side 30 wall of the tube at one point, while in the embodiment of the invention shown in Figure 4, this opening is formed by grinding or filing the end of the tube to form two "flats" 46, converging towards the end, and extending sufficiently far back from the end of the tube, as to expose the interior of the tube on the two sides beyond the depth of the recess of the tip 11.

This opening (44, 45, or 46) establishes communication between the interior of the air chamber 6, and the discharge opening 12 of the sprayer. 45 Thus, the air pumped into the chamber 6 (and also into the vacant portion of the container 23) exerts a pressure on the surface of the liquid within the container 23, and also discharges a jet of air through the opening 12. The air discharging through the opening 12 meets the liquid forced up through the tube 15 by the static pressure of the air, and the liquid is entrained in the air stream and is carried out in the form of a 50 fine spray.

This spray tends to be more or less continuous, notwithstanding the reciprocating motions of the piston. Thus, the check valve 21 entraps the air within the chamber 6 (and within any vacant 55 portion of the container 23) and the air may be stored at sufficient pressure to give continuity to the spray.

The sealing gasket or washer 47 of any suitable sealing material (cork, rubber, fiber, or the like) 60 seals the cylinder 5 into the container 23, thereby establishing a completely enclosed air chamber.

In the forms of construction shown in Figures 1, 3 and 4, the tube 15 is permanently fixed and 65 immovable with respect to the cylinder 5, while in the embodiment of the invention shown in Figure 2, the tube (now designated by the numeral 48) is removable when the cylinder is unscrewed from the container 23.

70 In the embodiment of the invention shown in

Figure 2, the tube 48 is preferably formed with a resilient loop 49 (the tube being of brass, bronze, or other more or less resilient material), and is also provided with a locking notch or double bend 50, which is adapted to engage the edge of the 5 opening 21 so as detachably to retain the tube 48 in position. Thus, the tube is supported between the recess of the tip 11 and the edge of the opening 21. When it is desired to remove the tube 48, the lower end of the tube is bent 10 until the notch 50 is loosened, and the end of the tube may then be removed from the recess of the tip 11 and completely removed from the air chamber.

The invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I hereby claim as new and desire to secure by Letters Patent, is:

1. A liquid sprayer including a liquid reservoir, an air chamber in communication with said liquid reservoir, a quick-detachable and sealed connection between said air chamber and said liquid reservoir, a generally conical nozzle forming a front terminal of said air chamber and having a spray-discharge opening therein, a liquid-conducting tube extending from said spray-discharge opening in the air chamber, into the liquid reservoir in proximity to the bottom thereof, an opening in the side of said tube near the discharge end thereof, a pump cylinder surrounding said air chamber and extending beyond the same, a pump piston operatively disposed within said pump cylinder, and a check valve intermediate the pump cylinder and said air chamber; said air chamber, said nozzle and said cylinder being secured to each other by a common, annular, interfolded and interlocking seam.

2. A liquid sprayer including a pump-cylinder, 45 an air chamber disposed within the front end of said cylinder, a check valve intermediate said air chamber and said pump-cylinder, and opening in the direction of the air chamber, a spray-discharge opening in the front end of said air chamber, a liquid reservoir detachably connected with said air chamber in communicating relation therewith when connected, and with the connection therebetween sealed with respect to the exterior, a liquid-conducting tube extending from 50 said spray-discharge opening into the liquid reservoir, and a pump-piston operatively disposed within said pump-cylinder; said pump-cylinder and said air-chamber being secured to each other by means of an outer, terminal, annular interfolded and interlocking seam.

3. A liquid sprayer including a pump-cylinder, an air chamber telescoped into the front end of said pump-cylinder and having an outer end wall, a spray-discharge opening in said outer end wall, a check valve intermediate the inner wall of said air chamber and said pump-cylinder, opening in the direction of the air chamber, a liquid reservoir, a quick-detachable coupling intermediate said air chamber and said liquid 65 reservoir for forming mechanical connection between the two and for establishing a sealed air-passageway between the two, a liquid-conducting tube extending from said spray-discharge opening through said air-passageway into said liquid 70 reservoir.

reservoir, and a pump-piston operatively disposed within said pump-cylinder; said pump-cylinder and said air chamber being secured to each other by means of an outer, terminal, annular inter-
5 folded and interlocking seam.

4. A liquid sprayer including a liquid reservoir, an air chamber in communication with said liquid reservoir, a quick-detachable and sealed connection between said air chamber and said liquid reservoir, a spray-discharge opening in said air chamber, a liquid-conducting tube extending from said spray-discharge opening in the air chamber, into the liquid reservoir, in proximity to the bottom thereof, a pump-cylinder opera-
10 tively connected with said air chamber, a pump-piston operatively disposed within said pump-cylinder, and a check valve intermediate the pump-cylinder and said air chamber; said air chamber and said pump-cylinder being secured to each other by an annular, interfolded and in-
15 terlocking seam at the front end of each.

5. A liquid sprayer including a pump-cylinder, an air chamber connected with said pump-cylinder through an annular seam formed of interlocking folded peripheral flanges on the two connected members respectively, a liquid reservoir, a quick-detachable coupling member intermediate said air chamber and said liquid reservoir and having an air passageway therethrough connecting said air chamber and said liquid reservoir, a spray-discharge opening in the front end of said air chamber, a liquid-conducting tube extending from said spray-discharge opening in the air chamber through said air-passageway into said liquid reservoir; said spray-discharge opening being in direct communication with said air chamber, a pump-piston operatively disposed within said pump-cylinder, and a check valve intermediate said pump-cylinder and said air-
30 chamber, opening towards the latter.

40 6. A liquid sprayer including a pump-cylinder an air chamber communicable therewith; said air chamber having a front terminal wall including a spray-discharge opening there-
45 through, a tube retainer member within said air chamber, a check valve intermediate said air chamber and said pump-cylinder, opening in the

direction of the former, a liquid reservoir in communicating relationship with said air chamber, a quick-detachable coupling intermediate said air chamber and said liquid reservoir, a liquid-conducting tube extending from said spray-discharge opening through said retainer member, through said quick-detachable coupler into said liquid reservoir, and being fixedly secured to said retainer member, and a pump-piston operatively disposed within said pump-cylinder; said spray-
10 discharge opening being at all times in direct communication with said air chamber; said pump-cylinder and said air chamber being secured to each other in sealed relation to each other, by means of an interfolded and interlocking annular seam surrounding their front ends.
15

7. A liquid sprayer including a cylinder, one portion of which is a pump chamber, a cylindrical member having an apertured end wall thereon and embraced by the forward end of said cylinder, said end wall forming the rear end of an air chamber and the front wall of said pump chamber and having a check valve thereon for preventing flow of air through its aperture from the air chamber back to the pump chamber, an apertured cap member fixed to the forward ends of said cylinder and said cylindrical member to act as the forward wall of said air chamber, a fastening cap secured to the exterior of said cylinder, said fastening cap, cylinder and cylindrical member having registering apertures therethrough within the area of the cylinder contacted by said fastening cap, a receptacle for liquid to be sprayed detachably secured to said fastening cap, a tube for conducting liquid to be sprayed from said receptacle to the aperture in said cap member and means for sealing the joint between said cylinder and said cylindrical member at the edges of said registering apertures therethrough.
40

8. A liquid sprayer as set forth in claim 7, and in which the cylinder, the cylindrical air member and the cap member are secured to each other in sealed relation to each other by means of an interfolded and interlocking annular seam surrounding their front ends.

ROBERT M. BAGLEY.
